UNITED STATES PATENT OFFICE.

JOSEPH STEVENS, OF SAN FRANCISCO, CALIFORNIA.

STEAM-BOILER.

SPECIFICATION forming part of Letters Patent No. 294,927, dated March 11, 1884.

Application filed December 7, 1883. (No model.)

To all whom it may concern:

Be it known that I, JOSEPH STEVENS, of the city and county of San Francisco, and State of California, have invented an Improvement in Steam-Boilers; and I hereby declare the following to be a full, clear, and exact description thereof.

My invention relates to certain improvements in steam-boilers; and it consists of a lower portion composed of alternate series of horizontal tubes crossing each other at right angles, their ends opening into vertical water-legs, which form the sides and inclose the grate and fire-space, a combined steam and water drum situated above the tubes, and circulating-pipes connecting this drum with the vertical water-legs at top and bottom.

Referring to the accompanying drawings for a more complete explanation of my invention, Figure 1 is a perspective exterior view of my boiler. Fig. 2 is a vertical section taken longitudinally through the cylindrical portion. Fig. 3 is a horizontal section.

The lower part of my boiler is shown in the present case square in form, and consists of water legs or spaces A, which form the walls.

Near one end is the fire-place and grate B, and the escape pipe or flue C leads out from the opposite end, also near the bottom. A diaphragm, D, extends up to or near the top and across from side to side of the interior space, and this directs the flame and products of combustion upward, and then down upon the opposite side to the escape-flue, so as to produce the greatest heating effect. Tubes E extend across the interior space between the walls in horizontal rows, their ends opening into the water-spaces A, and other tubes, F, may extend across between the first-named rows and at right angles with them, also opening into the end water-spaces, so as to produce a complete connection of all parts. Above this portion of the boiler is a cylindrical portion, G, supported by walls, so that the heat passing upward from the furnace may act upon

its lower side. From the upper part of the water-legs A a steam pipe or pipes, H, connect with the lower part of this cylinder, and circulating-pipes I lead from the bottom of the cylinder to the bottom of the water-spaces A, as shown. Water fills the whole of the square lower part of the boiler, and also a part of the cylindrical steam-drum G. The steam generated in the lower tubular portion of the boiler passes up into the cylinder along with the water from the upper part of the generator, and the pipes I return it again to the bottom of the part A, thus keeping up a rapid and complete circulation.

In the construction of multitubular boilers great difficulty is experienced in preventing the water being driven out of the lower tubes by the rapid ebullition, and the consequent injurious heating of the tubes. This invention is designed to prevent this, and to provide a complete and rapid circulation of the water, which is more effectually done by the combination with the transverse tubes of the cylinder above and the connecting-pipes.

Having thus described my invention, what I claim as new, and desire to secure by Letters Patent, is—

In a steam-boiler, the rectangular water-legs, with the horizontal pipes uniting the spaces upon opposite sides, the fire-place and chimney situated at the bottom and at opposite ends, and the vertical diaphragm or bridge-wall between, in combination with the cylindrical water and steam containing shell situated above and exposed to the heat of the furnace, as shown, and the circulating-pipes connecting the water-space of the cylinder with the upper and lower part of the water-legs, substantially as herein described.

In witness whereof I have hereunto set my hand.

JOSEPH STEVENS.
